CLAIM

The ornamental design for an envelope for mailing and return, substantially as shown and described.

DESCRIPTION

FIG. 1 is a front elevational view of a first embodiment of an envelope for mailing and return showing my new design;

FIG. 2 is a front elevational view thereof, showing the envelope in a partially folded condition;

FIG. 3 is a front elevational view thereof, showing the envelope in an alternate folded condition;

FIG. 4 is a front elevational view thereof, showing the envelope in an alternate folded condition;

FIG. 5 is a front elevational view thereof, showing the envelope in a closed condition;

FIG. 6 is a front elevational view thereof, showing the envelope in an alternate folded condition, exactly like FIG. 4;

FIG. 7 is a front elevational view thereof, showing the envelope in an alternate folded condition;

FIG. 8 is a front elevational view thereof, showing the envelope in a closed condition;

FIG. 9 is a front elevational view thereof, showing the envelope in an alternate folded condition;

FIG. 10 is a front elevational view thereof, showing the envelope in an alternate folded condition;

FIG. 11 is a front elevational view thereof, showing the envelope in an alternate folded condition;

FIG. 12 is a front elevational view of a second embodiment of an envelope for mailing and return showing my new design; and,

FIG. 13 is a front elevational view thereof, showing the envelope in a closed condition.

The portion of the disclosure shown in broken lines represents structural environment and forms no part of the claimed design.
